(57) **CLAIM**

The ornamental design for a gas adaptor for electric generator, as shown and described.

DESCRIPTION

FIG. 1 is a front, top, and right side perspective view of a gas adaptor for electric generator, showing our design.

FIG. 2 is a back, top and left side perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures illustrating portions of the gas adaptor for electric generator form no part of the claimed design.
